SOFA BED

Robert A. Burton, High Point, N. C., assignor to
The Automatic Hinge Co., High Point, N. C., a
partnership

Application April 12, 1944, Serial No. 530,615

6 Claims. (Cl. 5—47)

The present invention relates to sofa beds, and particularly to a hinge construction for pivotally connecting the seat and back sections of the sofa bed to each other and to the bed frame.

An object of the invention is the provision of a hinge construction which facilitates movement of the seat and back sections from one position to another and which positively locks the hinge against accidental movement in the sofa or "couch position" of the sofa bed.

Another object is to provide a sofa bed hinge which is simple in construction and at the same time, is highly efficient and easy to operate.

A further object is the provision of a sofa-bed hinge construction wherein a latch and dog are carried by one hinge member and a latch receiving element is carried by the other hinge member. Furthermore, the other hinge member is provided with a portion which functions to move the dog to release the latch from its notch and retain the latch in released position until the movement of the hinge member is reversed, whereupon a second portion of this hinge member will contact the dog and move it out of engagement with the latch to permit the latch to move into a position where it can again engage the notch.

With the foregoing and other objects in view, the invention will now be more fully described, reference being had to the accompanying drawings in which:

Figure 1 is an enlarged detail view, showing the hinge construction in full open or bed position.

Figure 2 is an enlarged detail view, showing the seat raised to permit the latch of one hinge member to engage the notch of the other hinge member and thereby lock the seat and back in one position of adjustment.

Figure 3 is a view similar to Figure 2, showing the back raised by the seat to a normal "couch use" position.

Figure 4 is a view showing the seat lifted and moved far enough to the rear to cause the dog to release the latch from its notch and retain the latch in released position.

Figure 5 is a view showing the dog tripped to release the latch in the downward movement of the seat.

Figure 6 is a fragmentary view of the associated seat, back and hinge members.

Figure 7 is a vertical section taken on line 7—7 of Figure 1.

Figure 8 is an enlarged view of the hinge showing the hinge members in bed position, and

Figure 9 is a reduced end elevation of the complete sofa-bed.

Referring now to the drawings, and particularly to Figure 9, there is disclosed a sofa bed 10 incorporating the construction of the present invention. This bed comprises a base or frame 11, supporting the seat and back sections 12 and 13, respectively. As is usual in pieces of furniture of this type, the base or bed frame 11 is of substantially rectangular formation, comprising front and rear panels 14 and 15, respectively, and end panels 16. Legs or other suitable supporting elements 17 are attached to the base 11 and support the same in slightly elevated position.

Upon the inner face of each end panel 16, is mounted linkage mechanism 18 which in turn is connected to a hinge 19, whereby the seat and back sections may be moved to different positions of adjustment relatively to the base or frame 11.

The linkage mechanism may be of the usual construction employed in furniture of this character and consists of a bar 20 rigidly secured to the inner face of its respective end panel 16. Links 21 and 22 have their lower ends pivotally secured to the front and rear ends respectively, of the bar 20. The hinge 19 constituting the subject of this invention comprises a pair of hinge members

23 and 24. Since hinge member 23 is secured to the seat section 12, it will be designated as the seat hinge member. Member 24, which is secured to the back section 13, will be designated as the back hinge member.

The upper end of link 21 is connected by a common pivot 25 to both hinge members 23 and 24 adjacent their upper ends. This forms the pivot connecting these hinge members and permits swinging movement of these members relative to each other about the pivot 25. The upper end of link 22 is pivoted to back hinge member 24 adjacent its upper end, as at 26. It is to be understood that there are separate sets of linkage mechanism and hinge members at each end of the sofa bed, but since these are substantially identical in construction, only one set will be described in detail.

Referring to Figures 1, 6 and 8, it will be observed that seat hinge member 23 is substantially flat in formation and extends upwardly and rearwardly from a base 27 constituting a right angled flange integral with the lower edge of the seat hinge member. This base or flange 27 is secured to an end rail 28 forming a part of the frame structure of the seat section 12. The back hinge member 24 is also substantially flat in formation

and is provided with a lower right angled flange

29, similar to the flange 27. This flange is secured to an end rail 30 forming a part of the frame structure of the back section 13.

The flange 28 does not extend entirely to the inner edge of the hinge section 24 but terminates at a point rearwardly of said inner edge. At a point between the inner end of the flange 29 and the inner edge of the member 24 is located a latch 31 which is pivotally mounted on the member 24 as at 32. As shown in Figures 1 and 8, this pivot point 32 is adjacent to the lower edge of the member 24 and the latch 31 is of such a length that its free end extends substantially to the inner end of the member 24. In the bed position of the hinge, such as shown in Figure 8, the latch 31 normally engages the curved lower edge 33 of the seat hinge member 23. Any suitable means such as the spring 34 may be provided to urge the upper edge 35 of the latch into engagement with the edge 33 of the seat hinge member 23. The spring 34 is of substantially U-shaped formation and has the end of its lower arm 36 anchored in an opening 37 located in the lower portion of the back hinge member 24. The end of the upper arm 38 of the spring passes through an opening 39 in the latch 31 and is additionally anchored to the latch by means of a struck up and bent over strap 40 which forms an integral part of latch 31.

The upper edge 35 of the latch is provided with a notch 41 adjacent the pivot point 32. This notch is adapted to be engaged by the corner portion or projection 42 of a dog 43 as will be hereinafter described in detail. This dog is pivoted as at 44 to the flat face of the back hinge member 24 at a point slightly above the latch 31. A pin or projection 45 is located above the dog to limit upward movement of the dog about its pivot. In addition to projection 42, the dog is provided with a pointed projection 46 for engagement with a portion of the seat hinge 23 as will also be described in detail hereinafter.

It will be observed that the curved portion 33 of the seat hinge member 23 is located somewhat above the base or flange 27 of said seat hinge member. That is, the flat surface of the member 23 has been cut away adjacent its lower end to provide a space for the reception of the latch 31 whereby the upper edge 35 of the latch may contact the edge 33 and slide along the same when the member 23 is moved about its pivot relatively to the member 24.

Referring again to Figure 8, it will be observed that the lower curved edge 33 of the seat hinge member 23 is provided with a notch 47 adjacent its inner edge. This notch is preferably formed by cutting out and striking up a portion of the flat surface of the member 23 so as to not only provide the notch 47 but also a post 48 which constitutes means for preventing the dog 43 from accidentally sliding over the surface of the member 23 in the event that the pivots should become sufficiently loose to permit this movement to take place. It will also be observed that the lower inner edge of the back hinge member 24 is struck up to provide the post 49, which constitutes means to prevent the latch 31 from dropping below a predetermined point. This post 49 also prevents the seat hinge member 23 from swinging or opening too far. In other words, the inner vertical edge 50 will strike the post 49 in the event that the hinge member 23 is moved inwardly too far when being swung down to its horizontal bed position.

In the position shown in Figure 8, the seat hinge member 23 is provided inwardly of its pivot 25 with a projection or finger 51 which is located ad-

jacent the notch 47 and is adapted to engage the V-shaped projection 46 and move the dog 43 downwardly about its pivot when the hinge member 23 is moved from one position of adjustment to another. The seat hinge member 23 is also provided with a top projection or finger 52 which is spaced from and connected to the projection 51 by a curved edge 53 which forms with said projections a pocket for receiving the dog 43, as will be hereinafter described in detail.

Referring to Figures 1, 2, 3 and 9, and assuming that it is desired to move the seat and back sections 12 and 13 from their bed position shown in Figures 1 and 9 to the sofa or "couch use" position, this is accomplished by initially swinging the seat section 12 about its pivot 25 to the position shown in Figure 2. During this movement of the seat section about its pivot, the latch 31 will slide on the lower curved edge 33 of the seat hinge member 23 until it engages the notch 47. When this has been accomplished, the position of the seat is then reversed. That is, it is swung downwardly to its horizontal position and because of the interlocking connection between the latch 31 and the notch 47, the back section 13 will be moved to its normal operative position shown in Figure 3. It will be observed that the construction of the latch and notch is such that the pressure exerted on the back when in normal use will have the effect of urging the latch into interlocking engagement with the notch. It is to be understood, of course, that the spring 34 constantly urges the latch 31 toward the seat hinge member 23. Thus, a relatively solid and rigid construction is provided which will withstand the normal strain and stress imposed upon the sofa bed.

When it is again desired to move the back and seat sections to their horizontal position shown in Figure 1, this may be easily and quickly accomplished by initially swinging the back section to a substantially horizontal position such as shown in Figure 2. This movement will raise the seat section 12. Thereafter, the seat section should be moved further about its pivot to the position shown in Figure 4. This further movement, that is, the movement of the seat from the position shown in Figure 2 to that in Figure 4, will bring into operation the top projection or finger 52 of the seat hinge section 23. The hinge section 23, of course, swings about its pivot during movement of seat section 12 and in the present instance brings the projection 52 into engagement with the pointed projection 46. This will swing the dog 43 downwardly about its pivot so that the projection 42 on the dog will engage the top edge 35 of the latch and move it out of engagement with the notch 47 as the hinge member 23 is further moved about its pivot. The projection 42 of the dog will continue to slide along the top edge 35 of the latch until it engages the latch notch 41. When this is accomplished, the dog will retain the latch in its released position so that the seat section 12 may be removed in the reverse direction, that is, downwardly to the horizontal bed position. Just before the seat section 12 moves to its extreme horizontal position, the dog 43 is released from the latch notch 41 to permit the latch to again engage the curved edge 33 of the seat hinge member 23 so that it will be in a position to slide along said edge and engage the notch 47 when the seat section 12 is subsequently raised to the position shown in Figure 2.

Referring to Figure 5, there is disclosed the means for disengaging the dog 43 from the latch

notch 41. As the seat section 12 is swung to the position shown in Figure 5, the projection 51 of the hinge member 23 engages the free edge portion 54 of the dog 43. This will have the effect of moving the dog about its pivot 44 and thus raise the projection 42 out of engagement with the notch 41. As soon as this is accomplished, the spring 34 is free to urge the latch into engagement with the edge 33 of the hinge section 23, whereby the latch is in position to slide along the edge 33 and engage the notch 41 when the seat section is again moved from its bed position.

From the foregoing, it will be observed that the present invention provides a hinge which is quite simple in construction and which is capable of positively locking the seat and back sections in the sofa or "couch use" position of the sofa bed.

It will further be noted that the hinge structure is quite compact and flat and that certain of the operating elements such as the projections or fingers are in the same plane as the flat hinge member 23 and, in fact, constitute integral extensions of said member. While it has been stated that both sets of hinges are substantially identical in construction, it is to be understood that the hinge located at the opposite end of the sofa bed, from that illustrated in the drawings, will have its flanges 27 and 29 projecting in the opposite direction from the flanges 27 and 29 shown in Figure 6. That is, each set of flanges will face the other set. Likewise, the latch 31 and dog 43 of this last mentioned hinge will be mounted on the opposite face of the hinge member 24 from that disclosed in the drawings. That is, these elements will be on the inside surface of its hinge member and face the other latch and dog. It will be appreciated, however, that while these changes are necessary from a practical standpoint, they do not change the structural features and operation of the hinge. Thus, both hinges are substantially identical and function in the same manner.

Referring to Figures 1 and 8, it will be observed that the flange 29 is provided with a struck-up portion 55 overlying the base of the spring 34. This is for the purpose of preventing accidental displacement of this portion of the spring. Thus, the portion 55 cooperates with the strap 40 to anchor the spring in proper operating position.

It is to be understood that while the hinge construction is particularly designed and adapted for use in sofa beds or the like, it is capable of being employed for use in other devices. It is to be further understood that the invention is not limited to the details of construction shown in the drawings and that the phraseology employed in the specification is for the purpose of description and not of limitation.

I claim:

1. In a sofa bed having a back and a seat movable as a unit out of their sofa-forming positions and also movable relatively to each other, a hinge pivotally connecting said back and seat, said hinge comprising a first hinge member secured to the back, a second hinged member secured to the seat and pivoted to the first member in overlapping relation, said seat hinge member having a notch, a latch movably mounted on the back hinge member and normally urged into contact with the seat hinge member and adapted upon movement of said seat hinge member about its pivot to engage the notch and retain said hinge members in one position of adjustment, means movably carried by said back hinge member engageable with the latch to release it from the notch and thereby permit the seat section to move to the sofa position.

notch and to retain said latch in released position, means on said seat hinge member engageable with said first mentioned means to move said first mentioned means into retaining relation with the latch, and additional means on said seat hinge member engageable with said first mentioned means to move said first mentioned means out of retaining relation with the latch and thereby permit the latch to move into engagement with said seat hinge member.

2. In a sofa bed having a back and a seat movable as a unit out of their sofa-forming positions and movable relatively to each other, a hinge pivotally connecting said back and seat, said hinge comprising a pair of hinge members, each having a substantially flat surface, one of said hinge members being secured to the back, the other of said hinge members being secured to the seat and pivoted to the back hinge member in overlapping relation, said seat hinge member having an edge terminating in a notch adjacent its inner overlapped end, a latch pivotally mounted on the back hinge member below the notch edge of the seat hinge member and normally urged into contact with said edge, said latch upon movement of said seat hinge member being adapted to slide on said edge and engage said notch to thereby retain said hinge members in one position of adjustment, said latch having a notch formed in one of its edges, a dog pivotally mounted on said back hinge member above the latch and having a portion thereof slidable along said latch edge into engagement with said latch notch to release said latch from the notch on the seat hinge member and to retain said latch in released position, said seat hinge member having a portion thereof adapted when said seat hinge member is moved about its pivot in one direction, to move into engagement with the dog for controlling the latch releasing movement of said dog, said seat hinge member also having a portion thereof adapted when said seat hinge member is moved about its pivot in the reverse direction, to move into engagement with the dog to release it from the latch notch and thereby permit the latch to move into engagement with the edge of the seat hinge member.

3. In a hinge for a sofa bed, a pair of hinge members, each having a substantially flat surface, said members having portions of their flat surfaces arranged in overlapping relation and pivoted to each other within the overlapped area, one of said members having an edge termination in a notch adjacent its inner overlapped end, a latch movably mounted on the second hinge member adjacent the notched edge of the first hinge member and normally urged into contact with said edge, said latch upon movement of said first hinge member about its pivot being adapted to slide on said edge and engage said notch to thereby retain said hinge members in one position of adjustment, means movably carried by said second hinge member engageable with the latch to release it from the notch and to retain said latch in released position, means on said first hinge member engageable with said first mentioned means to move said first mentioned means into retaining relation with the latch, and additional means on said first hinge member engageable with said first mentioned means to move said first mentioned means out of retaining relation with the latch and thereby permit the latch to move into engagement with the edge of the first hinge member.

4. In a hinge for a sofa bed, a pair of hinge

members, each having a substantially flat surface, said members having portions of their flat surfaces arranged in overlapping relation and pivoted to each other within the overlapped area, one of said members having an edge terminating in a notch adjacent its inner overlapped end, a latch pivotally mounted on the second hinge member adjacent the notched edge of the first hinge member and normally urged into contact with said edge, said latch upon movement of said first hinge member about its pivot, being adapted to slide on said edge and engage said notch to thereby retain said hinge members in one position of adjustment, said latch having a notch formed in one of its edges, a dog pivotally mounted on said second hinge member and having a portion thereof slidable along said latch edge into engagement with said latch notch to release said latch from the notch on the first hinge member and to retain said latch in released position, said first hinge member having a portion thereof adapted when said first hinge member is moved about its pivot in one direction, to move into engagement with the dog for controlling the latch releasing movement of said dog, 25 said first hinge member also having a portion thereof adapted when said first hinge member is moved about its pivot in the reverse direction, to move into engagement with the dog to release it from the latch notch and thereby permit the latch to move into engagement with the edge of the first hinge member.

5. In a hinge for a sofa bed, a pair of hinge members, each having a substantially flat surface, said members having portions of their flat surfaces arranged in overlapping relation and pivoted to each other within the overlapped area, one of said members having a curved lower edge portion terminating in a notch adjacent its inner overlapped end, said member having a projection located inwardly of the notch and a second projection spaced from and above the first projection, a latch pivotally mounted on the second hinge member below the curved lower edge portion of the first member and normally urged into engagement with said edge, said latch having a notch formed in its top edge, a dog pivotally mounted on said second hinge member above
